UNITED STATES PATENT OFFICE.

CHARLES V. BUSCH, OF BUFFALO, NEW YORK.

DESIGN FOR A BADGE OR SIMILAR ARTICLE.

SPECIFICATION forming part of Design No. 34,304, dated April 2, 1901.

Application filed January 28, 1901. Serial No. 45,151. Term of patent 8½ years.

To all whom it may concern:

Be it known that I, CHARLES V. BUSCH, a citizen of the United States, residing at Buffalo, in the county of Erie and State of New York, have invented and produced a new and original Design for a Badge or Similar Article, of which the following is a specification, reference being had to the accompanying drawings, forming a part thereof.

This design relates to the configuration and ornamentation of a badge or similar article.

In the accompanying drawings, Figure 1 is a face view of a badge embodying my design, and Fig. 2 is a horizontal section thereof in line 2 2, Fig. 1.

The leading feature of my design consists of a plate A, having the outline of the figure

of a buffalo standing at charging posture, with the head, mane, horns, legs, and tail in bas-relief, a convex disk or circular field B, 20 arranged centrally on the face of the plate A and located wholly within the outline thereof, and the representation C of the Western Hemisphere arranged upon the disk B.

What I claim is—

The design for a badge or similar article, substantially as herein shown and described.

Witness my hand this 16th day of January, 1901.

CHARLES V. BUSCH.
